UNITED STATES PATENT OFFICE.

EMIL A. PETERSON, OF APPLETON, WISCONSIN, ASSIGNOR OF TWO-THIRDS
TO VALLEY IRON WORKS COMPANY, OF APPLETON, WISCONSIN, A COR-
PORATION OF WISCONSIN.

FLUSHING DEVICE FOR RAG-ENGINE VATS.

No. 843,965.

Specification of Letters Patent.

Patented Feb. 12, 1907.

Application filed September 10, 1906. Serial No. 333,889.

To all whom it may concern:

Be it known that I, EMIL A. PETERSON, a citizen of the United States, residing at Appleton, county of Outagamie and State of Wisconsin, have invented new and useful 5 Improvements in Flushing Devices for Rag-Engine Vats, of which the following is a specification.

My invention relates to improvements in 10 flushing devices for rag-engine vats.

The object of my invention is to provide improved means to facilitate emptying the vats after the beating operation is completed.

In the following description reference is had 15 to the accompanying drawings, in which—

Figure 1 is a plan view of my invention. Fig. 2 is a detail view of a portion of one inner face of the vat, showing the floor in section; and Fig. 3 is a sectional view drawn on 20 line x x of Fig. 1.

Like parts are identified by the same reference characters throughout the several views.

1 is the vat of a rag-engine; 2, the mid- 25 feather; 3, the front fall, and 4 the back fall, the movable member being omitted. A water-conducting pipe 6 extends from near the front fall around the outer wall of the vat into the back fall and then transversely of the 30 vat underneath the back fall, as indicated at 7, to a point near the mid-feather and then rearwardly along the base of the mid-feather, as indicated at 8, and then around and along the outer side of the mid-feather, as at 9, to 35 the forward end thereof, where it is again turned inwardly along the inner face of the mid-feather, as indicated at 10, the pipe being therefore made substantially continuous with the exposed base of the outer wall on the 40 inner side and to also extend along the exposed base of the mid-feather on both sides. This pipe is covered by an inclined shield 12, the lower margin of which is mounted upon 45 blocks 13 on the floor of the vat, leaving narrow apertures 14 between the blocks 13 and between the floor of the vat and the edge or 50 margin of the shield 12. The pipe, of which the various sections are marked 6 to 10, inclusive, is provided with apertures 15 in its inner and lower side, whereby water is permitted to escape from the pipe in the direction of the floor of the vat and also in the direction of the narrow openings 14. With this

arrangement water can be discharged along the floor of the vat simultaneously from all 55 of the exposed walls, the entire body of pulp in the vat being simultaneously floated or lifted from the bottom.

The vat is preferably provided with two outlets, one near each end. These outlets 60 are each formed in the usual manner, the floor being provided with a countersunk ring 21, which forms a seat for a lid-valve 22, which normally covers the opening. When it is desired to empty the vat, these lids are 65 lifted from the openings and water is admitted through a supply-pipe 23, which extends from any suitable source of supply (preferably under pressure) through the outer wall of the vat and connects with the pipe 6 70 at any convenient point.

If desired, the pipe-sections 7, 8, 9, and 10 may be omitted, since the pipe 6 fully encircles the exposed base of the outer wall and is therefore capable of discharging the flushing- 75 currents across the floor of the vat from all sides. By extending the pipe around the exposed base of the mid-feather, however, any tendency of the pulp to wash toward these 80 points is avoided.

In referring to the exposed base of the outer wall and mid-feather it will of course be understood that I refer to those portions of the wall and mid-feather which are not covered in whole or in part by the front fall and 85 back fall. In other words, I refer to those portions of the outer wall and mid-feather which are exposed to the water or other contents of the vat along the floor thereof, even though partially covered by the shield 12. 90

Having thus described my invention, what I claim as new, and desire to secure by Letters Patent, is—

1. The combination with the vat of a rag-engine, of a pipe connected with a source of 95 water-supply and extending along the base of the outer wall and provided with perforations adapted for the discharge of water inwardly along the floor of the vat, and a shield extending over the pipe downwardly 100 and inwardly from the side of the vat to a point near the floor thereof.

2. The combination with the vat of a rag-engine, of a pipe connected with a source of 105 water-supply and extending along the base of the outer wall and provided with perfora-

tions adapted for the discharge of water inwardly along the floor of the vat, and a shield extending over the pipe downwardly and inwardly from the side of the vat to a point near the floor thereof, the lower margin of said shield being supported from the floor at intervals by suitable spacing-blocks.

3. The combination with a vat of a rag-engine, of a pipe connected with a source of water-supply and extending along the inner face of the outer wall, and substantially continuous with the exposed base thereof; and

a shield covering said pipe to a point in close proximity to the floor; said pipe being provided with perforations adapted to permit the discharge of water from the pipe along the floor and under the shield. ¹⁵

In testimony whereof I affix my signature in the presence of two witnesses.

EMIL A. PETERSON.
